WIRE INSULATION STRIPPER

James E. Woolman, United States Army,
Elkton, Md.

Application February 8, 1945, Serial No. 576,867

7 Claims. (Cl. 81—9.51)

(Granted under the act of March 3, 1883, as
amended April 30, 1928; 370 O. G. 757)

1

The invention described herein may be manufactured and used by or for the Government for governmental purposes, without the payment to me of any royalty thereon.

The present invention concerns a wire insulation stripper.

It is an object of the invention to provide means whereby insulation may be readily removed from wire or the like to be used in electric circuits.

It is an object of the invention to provide an insulation stripper for readily and rapidly removing the insulation from the high tension leads in an aeroplane engine or the like.

It is an object of the invention to construct a wire insulation stripper to be utilised with stranded high tension leads whereby the insulation may be stripped from a given measured length of an end of the lead without nicking any strand thereof.

It is an object of the invention to provide means to remove the insulation from a stranded conductor intended to carry high frequency current at high voltage without the danger of leakage and resultant radio interference caused by nicking one or more of the strands of the conductor.

It is an object of the invention to provide means to remove measured lengths from the end of stranded conductors in a minimum of time and without the care and skill normally required when such an operation is performed by hand.

It is an object of the invention to provide a wire insulation stripper which is cheap and sturdy in construction and which may readily be built from materials at hand.

Reference will be had to the drawings in which one form the invention may take is disclosed. Like numbers refer to like parts throughout.

Figure 1 is a perspective view of an assembly of the device.

Figure 2 is a plan view of the invention shown in Figure 1.

Figure 3 is a side elevation of the invention.

Figure 4 is an end elevation of the invention with its mounting indicated.

Figure 5 is a plan view of the lower base block of the device.

Figure 6 is a side elevation of the upper block of the device.

Figure 7 is a plunger pin detail.

Base block 10 is a lower section of the device which has a step-like break in its bottom side, as shown in Figure 5 whereby it is provided with an enlarged portion 11 and a thin portion 12. A central longitudinal fin 13 extends along thin por-

tion 12 of said base block 10 toward the enlarged portion 11, being spaced therefrom as at 14. Fin 13 is somewhat thicker than the diameter of the wire or cable to be stripped, but is considerably thinner than the diameter of the insulation. The enlarged portion 11 has a central longitudinal passage 15 therethrough adjacent the lower surface thereof and aligned with fin 13 as shown in Figure 4.

On the side of base block 10 opposite fin 13, but extending into that part comprising enlarged portion 11 are two spaced V-shaped slits 16 and 17. Slits 16 and 17 are positioned respectively one and one and a half inches from the end of fin 13, and extend downwardly into passage 15. Holes 18 and 19 are provided in the same face of base block 10 as slits 16 and 17 and positioned centrally of said slits respectively. Holes 18 and 19 stop short of passage 15. A hole 20 extends through the base block 10 adjacent the centre thereof and parallel to hole 18. The lower portion of hole 20 is counterbored as at 21 forming enlarged opening 21 positioned adjacent space 14. Threaded holes 22 and 23 are provided at each end of base block 10 for assembly purposes. An upper mating portion 24 is provided with counter-sunk holes 25 and 26 whereby it may be attached by machine screws or the like to base block 10. Slots 27 and 28 are positioned to mate with wedge-shaped slits 16 and 17 respectively. Said slots are of considerable depth and extend entirely across upper portion 24 but are wider than the slits to provide shoulders or abutments 16' and 17' at the top of the slits. Holes 29 and 30 are contained in upper portion 24 in such position as to register with and to form a continuation of holes 18 and 19 respectively. Hole 31 extends through upper portion 24 and is likewise positioned to register with and form a continuation of hole 20 in base block 10. Transverse holes 32 and 33 are provided in upper portion 24 for mounting purposes as will hereinafter appear.

A plunger 34 is provided with an enlarged head 35 and a shank 36 of such diameter as to slide freely in holes 18 and 19. The bottom portion of plunger 34 has a longitudinal slot 37 of such size as to snugly receive the head of a single edged razor blade 38 inserted endwise into the slot from the side of the plunger. A narrow slotted portion 39 permits the blade portion to project from the end of plunger 34 and provides shoulders 40 which bear against the under side of the head portion of the razor blade and hold it in position. A similar unslotted plunger 41 fits hole 20. Plungers 34 and 41 are provided with compression springs

42. Plunger 41 may have a ring 43 or the like pressed on its lower end and of such size as to seat in counterbore 21, holding plunger 41 in position with its spring 42 slightly compressed. Plungers 34 in holes 18 and 19 are held in position with the razor blades clear of the passage 15 by the action of the compression springs 42, the outward movement of each plunger being stopped while the spring is under slight compression by the abutment of the top or head of the razor blade with the upper wall of its confining slot 27 or 28 against which it is held by the action of the shoulders 40 of the plunger on the underside of the head portion of the blade. Mounting rods 44 and 44' extend through and are slidable in holes 32 and 33 and carry side mounting plates 45 and 46 on their outer ends. Mounting plates 45 and 46 have lower diverging extensions 47 and 48 respectively arranged to fit the standing edges on a jeweller's jaw vise. Spring clip portions 49 and 50 are mounted on the inner sides of plate members 45 and 46 and bear upon upper portion 24. Cotter pins 51 in rods 44 and 44' hold this portion of the assembly together.

The device is mounted by means of screws through diverging extensions 47 and 48 on a jaw vise of small size such as that commonly used by jewellers and the like. After the cutting operation the jaws of the vise are tightened so as to grip downwardly extending fin 13 and the cable insulation firmly. It will be noted that while the insulation is gripped firmly by the vise and compressed somewhat thereby, the relative size of the diameter of the metallic conductor and the thickness of fin 13 prevent the clamping action of the vise jaws from gripping the metallic conductor itself. Diverging flange-like portions 47 and 48 bear against the sloping sides of the jaws of the vise and cause springs 49 and 50 to press against upper portion 24, thus firmly mounting the assembly and holding it in position when the vise is loosened for the insertion of cable. The operation of the device is as follows:

The end of a wire to be stripped is inserted in the hole 15 until it touches the end of fin 13. As noted above the present device is particularly intended for high tension leads to the spark plugs of aircraft engines and the like. This wire is of special manufacture, quite expensive and usually stranded. In most installation an exact length of stripped wire is desired to make a connection. Should this length be exceeded an undesirable exposure of conductor will occur with a danger of short circuit. Should this length be insufficient a faulty joint or connection may be made which may subsequently result in engine failure.

If for a given installation it is desired to strip one inch of insulation from the end of the lead, the first plunger 34 or that in hole 18 is pressed downwardly so that the razor blade held in slot 38 in the lower portion of shank 36 is forced down almost through the insulation of the cable or conductor, the downward movement of the plunger being halted by the abutment of the lower edges of the head portion of the razor blade with the shoulders or stops at the top of the slits 16 at which time the cutting edge of the blade shall have penetrated the insulation to a point adjacent but short of contact with the metallic cable or conductor. The edge of the razor blade slides into V slits 16 which acts as a supporting guide. While the plunger 34 is depressed the cable or conductor is rotated through 360° thus making a clean cut through the insulation entirely around the conductor. It is particularly to be noted that

5 this operation does not raise a burr or other projection upon the metallic strands of the cable through which the leakage or high frequency high tension emanations may occur and interfere with radio reception.

When the complete peripheral cut is made the plunger 34 is released and rises under the action of spring 42, carrying the razor blade with it so that the blade entirely clears the cable insulation. The jaws of the vise are tightened and the cable is then withdrawn. The cut portion of insulation is held by the jaws of the vise and comes off cleanly leaving a square edge insulation on the cable. The jaws of the vise are then released and plunger 41 is depressed in hole 20 to eject the stripped cable portion. The device is now ready to strip the next lead. Should it be desired to strip an inch and a half of insulation the plunger in hole 19 is depressed and the operation described above repeated. It will be noted that the positioning of holes 18, 19 and 20 from the end of the fin 13 will be determined by the particular job that is desired to be done. For most purposes in airplane work an inch and an inch and a half are satisfactory stripped lengths.

15 If desired spring portions 49 and 50 may be eliminated and the mounting rods 44 and 44' press fitted into holes 32 and 33. For this purpose the central portions of mounting rods 44 and 44' may be roughened somewhat. The function of spring clip portions 49 and 50 is to centre the base block in the open space between the jaws of the vise so that an edge portion of a jaw will not interfere with the insertion of a piece of cable to be stripped. When mounting rods 44 and 44' are press fitted as above described, it will be seen that upon opening the vise that the action of mounting plates 45 and 46 on cotter pins 51 serves to centre base block 10 in such a manner that no interference is experienced from the jaws of the vise.

Having thus described the invention what is claimed is:

1. A wire insulation stripper comprising a body 45 having a longitudinal passage for the insertion of the insulated end of the wire to be stripped and having a transverse slot extending into the passage and having a bore positioned centrally of the slot and terminating short of the passage, 50 said slot having its open ends at the side of the body and being of a width and depth to slidably accommodate a conventional single edge razor blade inserted endwise therein through either of its open ends, a plunger mounted on the body for movement in a plane normal to the passage and having a slotted portion disposed in the bore to receive and support the razor blade with its cutting edge disposed passageward, tension means associated with the plunger and normally holding the latter and the cutting edge of the blade outwardly displaced with respect to the passage, said plunger being movable against the resistance of the tension means to cause the cutting edge of the blade to penetrate the passage, and blade-abutting means located in the slot to engage and abut the underside of the head portion of the razor blade for limiting the cutting action of the blade to the insulation around the wire.

2. A wire insulation stripper comprising a body having a longitudinal passage for the insertion of the insulated end of the wire to be stripped and having a transverse slot extending entirely across the portion of the body between the said passage and the upper surface of the body and forming

lateral openings in the body, the said slot comprising an upper rectangular portion of a width and depth to slidably accommodate a conventional single edge razor blade inserted endwise therein through either of the said lateral openings in the body and an inner portion converging to form a V-shaped slit extending into the passage, a movable blade carrier mounted on the body for movement in a plane normal to the passage and having a laterally and downwardly slotted portion disposed in the upper portion of the slot to receive and support the razor blade with its cutting edge disposed passageward and within the V-shaped slit of the lower portion of the slot, tension means associated with the blade carrier and normally holding the latter and the cutting edge of the blade outwardly displaced with respect to the passage, said carrier being movable against the resistance of the tension means to cause the cutting edge of the blade to penetrate the passage, and blade-abutting means located in the slot and at the top of the V-shaped slit to engage and abut the underside of the head portion of the razor blade for limiting the cutting action of the blade to the insulation around the wire.

3. A wire insulation stripper comprising a body having a longitudinal passage extending therethrough adjacent the lower surface thereof for the insertion of the insulated end of the wire to be stripped and having a transverse slot between the passage and the upper surface of the body and extending into the passage from one side thereof, said slot having its open ends at the sides of the body and being of a width and depth at its upper portion to slidably accommodate a conventional single edge razor blade inserted endwise therein and converging at its lower portion to provide a V-shaped slit in which the cutting edge of the blade is adapted to be received and guided, a movable blade carrier mounted on the body for movement in a plane normal to the passage and having a slotted portion disposed in the upper portion of the slot to receive and support the razor blade with its cutting edge extending into the V-shaped slit, and tension means associated with the blade carrier and normally holding the carrier and the blade outwardly displaced with respect to the passage with the cutting edge of the blade entirely clear of the passage, said carrier being movable against the resistance of the tension means to cause the cutting edge of the blade to penetrate the passage, the said slot having walls of its upper portion offset relative to the walls of its lower portion to provide blade-abutting shoulders located in the slot at the top of and on opposite sides of the V-shaped slit to engage and abut the underside of the head portion of the razor blade for limiting the cutting action of the blade to the insulation around the wire.

4. A wire insulation stripper comprising a body having a step-like break on one side thereof whereby it is provided with a thick portion and a thin portion, the said thick portion having a longitudinal passage for the insertion therethrough of the end of the insulated wire to be stripped, said passage opening out upon the said thin portion of the body, a stop on the thin portion of the said body and in alignment with but spaced from the passage to be engaged by the end of the wire subsequent to the emergence of the said end of the wire from the passage, the thickness of said stop being greater than the diameter of the wire to be stripped but less than

the diameter of the insulation to be removed, cutter means mounted on the thick portion of the body and movable into the passage for cutting the insulation of the inserted wire, and means associated with the thin portion of the body for mounting the stripper on a vise and including mounting members on opposite sides of the thin portion of the body and extending downwardly below the stop for engagement with the jaws of the vise, said mounting members being movable relatively to the body in a plane normal to the sides of the said thin portion and having diverging lower extensions to fit the standing edges of the vise and to be secured thereto for positioning the stripper on the vise so that adjacent portions of the stop and the space between the latter and the passage are in the path of movement of the jaws of the vise whereby the insulation of the inserted wire exposed in said space will be clamped and compressed between the jaws of the vise when the said jaws are tightened to grip the said stop, the size differential between the wire and the stop preventing the gripping action of the jaws from clamping the wire and permitting the latter to be withdrawn from the body subsequent to the cutting operation leaving the cut and stripped portion of the insulation between the jaws of the vise.

5. A wire insulation stripper comprising a body having a passage for the insertion therethrough of the end of the insulated wire to be stripped of the insulation, cutter means associated with the body and movable into the passage for cutting the insulation of the inserted wire, and a relatively thin flat plate associated with the body and positioned thereon in alignment endwise with but spaced axially from a terminal end of the passage with the end nearest the passage forming a stop to be engaged by the end of the inserted wire subsequently to the emergence of the said end of the wire from the said end of the passage whereby the portion of the insulated wire between the stop and the passage is in an exposed position adapting it to be gripped and held jointly with the stop by a clamping device, said plate having opposite side faces of substantial area to be gripped by a clamping device and separated by a thickness of material greater than the diameter of the wire to be stripped but less than the diameter of the insulation to be removed to prevent the gripping action of the clamping device from clamping and holding the wire against withdrawal from the body, whereby when said wire is withdrawn through the passage subsequent to the cutting and clamping operations the cut portion of the insulation will be retained by the clamping device and stripped from the wire.

6. A wire insulation stripper comprising a body provided on one side with a passage for the insertion therethrough of the insulated end of the wire to be stripped, a longitudinal fin on the body in line with but spaced from the passage to provide an abutment for the end of the inserted wire, said longitudinal fin being thicker than the diameter of the wire but considerably thinner than the diameter of the insulation on the wire, cutting means associated with the body and movable into the passage for cutting the insulation, mounting rods extending transversely through the body above and normal to the plane of the fin, mounting plates slidable on said rods and having lower diverging extensions adapted to be engaged with and fastened to the jaws of a vise for holding the stripper in position thereon with the fin between and in the path of movement of

the jaws, spring members carried by the plates on the inner faces thereof and adapted to bear against the adjacent sides of the body for centering the latter in the space between the open jaws of the vise, and means on the rods and outwardly of the plates to provide stops with which the plates are adapted to abut.

7. A device for removing insulation from a conductor comprising a body having a step-like break on one side thereof whereby it is provided with a thick portion and a thin portion, said thick portion having a conductor-receiving passage extending longitudinally therethrough and opening out upon the thin portion, gauging means associated with the said thin-body portion and supported thereby in longitudinally spaced relation to the thick portion of the body but in alignment with the said passage to be engaged by the end of the conductor subsequent to its emergence from the passage, cutting means associated with the thick portion of the body and movable into the

5 said passage to contact and cut the insulation of the conductor, and ejector means associated with the thin portion of the body and movable into the space between the gauging means and the thick portion of the body to engage and eject the stripped portion of insulation.

JAMES E. WOOLMAN.
